UNITED STATES PATENT OFFICE

133,610

DESIGN FOR A ROTARY TOOTHBRUSH

Denis Borgeat, Montreal, Quebec, Canada

Application April 30, 1942, Serial No. 106,760

Term of patent 14 years

To all whom it may concern:

Be it known that I, Denis Borgeat, a citizen of Switzerland, residing at 833 Cherrier Street, city of Montreal, Province of Quebec, Dominion of Canada, have invented a new, original, and ornamental Design for a Rotary Toothbrush, of which the following is a specification, reference being had to the accompanying drawing, forming part thereof.

Fig. 1 is a perspective view of a rotary toothbrush, showing my new design;

Fig. 2 is a side elevational view thereof; and

Fig. 3 is an end elevational view thereof.

I claim:

The ornamental design for a rotary toothbrush, as shown.

DENIS BORGEAT.
